HEADGEAR

Francis D. Huntsman, Salt Lake City, Utah

Application May 29, 1945, Serial No. 596,461

3 Claims. (Cl. 2-8)

1

This invention relates to means for adjusting the size of bands of headgear constituting carriers of eye, face, and head protectors, and the like, so that the gear may be made to conform comfortably and securely to heads of different perimeters.

It is an object of the invention to provide simple and reliable means by which size adjustments of headgear of that kind may be made easily and quickly.

Another object of the invention is to provide means for securely holding the bands in adjustment.

When considered with the description herein, characteristics of the invention are apparent in the accompanying drawing, in which an adaptation suitable for carrying shields of the welders' type is disclosed for purpose of exemplification.

Like reference-characters refer to corresponding parts in the views of the drawing, of which—

Fig. 1 is a plan view;

Fig. 2 is a view of a loop form of slide;

Fig. 3 is a section on line 3—3, Fig. 2;

Fig. 4 is a view of another form of slide;

Fig. 5 is a section on line 5—5, Fig. 4;

Fig. 6 is a view of the gear in elevation;

Fig. 7 is a view of another form of slide;

Fig. 8 is an edge view thereof;

Fig. 9 is a view of lapped end portions of a band and of parts associated therewith;

Fig. 10 is a section on line 10—10, Fig. 1;

Fig. 11 is an enlarged view of lapped portions of one of the bands.

The headgear shown by the drawing comprises a head encircling band 12 and a crown band 13. The latter band is fixed at its ends to the band 12 at diametrically opposite places thereon. Both bands have substantially parallel edges. They contact the head of the wearer when in use, and the crown band keeps the head band at the proper place on the head.

These bands may be of sheet metal or other suitable material. As now is conventional in the art, they may be made of compressed sheet fiber material, which is of light weight and is sufficiently stiff and strong for the purposes intended, and yet is susceptible of enough flexure for the bands to conform to the heads of users.

Each band is split and has an inner portion 14 and an outer end portion 15 that overlaps the inner portion.

The outer end portion of each band is formed with a plurality of aligned and spaced holes or seats 16, any one of which is engageable by a stud

or projection 17 fixed to the inner band portion near its end and projects outwardly therefrom.

The inner portion 14 of a band is formed at its end with integral finger pieces 18, which project laterally beyond the edges of the lapping outer portion 15.

A slide member 19 is fixed on the lapping portion 15 of each band, preferably at or near the end thereof, in order to maintain that portion close to the inner portion 14 on which the member is slidable. The slide member 19 may be a continuous loop-like flat structure that entirely surrounds the portions 14 and 15, as seen in Figs. 2 and 3.

15 It also may have a plate or web 20, with back-turned end parts 21 disposed over the edges and extending adjacent to the inner surface of the inner portion, as seen in Figs. 4 and 5.

A slide member 22 is movable along both band 20 end portions 14 and 15 between the slide member 19 fixed to the outer portion and the terminal of the inner portion 14. The member 22 may be of substantially the same form as the member 19; that is, like the forms shown by Figs. 2, 3, 4, and 5. It also may be as shown by Figs. 9 and 11, or as shown by Figs. 7 and 8.

25 As seen in Figs. 7 and 8, the member 22 comprises a plate or web 23, with back-turned end parts 24 disposed over the edges and extending adjacent to the inner surface of the inner band portion 14.

Normally, the stud or projection 17 of one band end portion is in retentive engagement with a hole or seat 16 of the other band end portion.

35 The slide member 22, when close to the stud or projection, keeps the two band ends close together and the pin or projection 17 from displacement from a hole or seat 16. Although the member 22 is slidable on the band, it is proportioned with respect to the band so that it frictionally is retained in the position to which it is moved.

40 In order that the slide member 22 may have position as close as practicable to the stud or projection 17 and thus more reliably keep the latter in a hole or seat, that member is formed so that parts thereof may assume place beyond or straddling the stud or projection.

45 For that purpose, the elements of the member that are disposed over the edges of the inner band portion 14 are cut back, as seen in Fig. 9, as at 25, to permit end parts of the slide to go over the finger pieces 18 and to straddle the stud or projection 17 as seen in Fig. 11.

55 Moreover, for the same purpose, the plate of

the slide may have an open-ended slot 26 to receive the pin, as seen in Fig. 7.

When it is desired to alter the size of either band of the headgear, the slide member 22 is moved away from the stud or projection 17 enough for end part of the inner portion 14 to be flexed. Then that part is free to be flexed inwardly (that is, away from the outer band portion 15) by fingers grasping the finger pieces 18 to release the stud or projection 17 from engagement with the hole or seat 16 in which it has been disposed. Upon release, thelapping portions of the band may be given relative movement by hands grasping the finger pieces and the slide member 19, to increase or decrease the size of the band. When adjustment is made, the stud or projection 17 is pulled by the finger pieces into engagement with a hole or seat 16, if the spring urge of the inner band does that. The slide 22 then is moved back to its engagement retaining position at the stud or projection.

Usually the headgear has pivots 27 at the diametrically opposite places of juncture of the head and crown bands, for the mounting thereon of a head shield, eye shield, or other head-carried device.

I claim:

1. In headgear of the character described, a head contacting band comprising lapping flexible inner and outer end portions slideable one against the other, one of said portions having a series of spaced seats, a stud on the other of said portions to selectively engage said seats, a laterally projecting finger piece on said stud-carrying portion near said stud, a slide member fixed to one of said portions near its end and having parts between which the other of said portions is slideable, and another member for holding said inner and outer band portions together and slideable thereon between said stud and fixed slide member to and from its holding position in transverse alignment with the stud.

2. In headgear of the character described, a head contacting band comprising lapping flexible inner and outer end portions slideable one against the other, one of said portions having

a series of spaced seats, a stud on the other of said portions to selectively engage said seats, a slide member fixed on one of said portions near its end and having parts between which the other of said portions is slideable, and another member for holding said inner and outer band portions together and slideable thereon between said stud and fixed slide member, said latter member including a web portion overlying said outer end portion and having a slot therein positioned to receive said stud when in holding position.

3. In headgear of the character described, a head contacting band comprising lapping flexible inner and outer end portions slideable one against the other, one of said portions having a series of spaced seats, a stud on the other of said portions to selectively engage said seats, a laterally projecting finger piece on said stud-carrying portion near said stud, a slide member fixed to one of said portions near its end and having parts between which the other of said portions is slideable, and another member for holding said inner and outer band portions together and slideable thereon to and from said stud, said latter member comprising a plate having opposed flange portions disposed over the edges of the band end portions and extending adjacent to the inner surface of the inner band portion and one of said flange portions being cut away in the provision of an elongated slot for receiving said finger piece when said latter member is in holding position.

FRANCIS D. HUNTSMAN.
